UNITED STATES PATENT OFFICE.

EMIL J. CARROLL, OF CINCINNATI, OHIO, ASSIGNOR TO THE AMERICAN LAUNDRY MACHINERY COMPANY, OF CINCINNATI, OHIO, A CORPORATION OF OHIO.

CONTINUOUS DRYING TUMBLER.

Application filed October 7, 1921. Serial No. 506,116.

To all whom it may concern:

Be it known that I, EMIL J. CARROLL, a citizen of the United States, residing at Cincinnati, in the county of Hamilton and State of Ohio, have invented certain new and useful Improvements in Continuous Drying Tumblers, of which the following is a specification.

This invention relates to drying tumblers for use in drying clothing, textile fabrics, or other similar materials which have been washed or subjected to dry cleaning operations and from which it is desired to remove moisture or cleaning fluids.

15 The object of the invention is to provide an improved drier of this kind which is continuous in operation and in which the materials to be dried can be handled in separate lots, as for example in the laundering of family washings where lot treatment is desirable to avoid marking separate articles.

Another object of the invention is to provide a drier in which separate batches or 25 lots of materials to be dried are enclosed in distinct containers which travel in turn through the drier and in which the clothes or materials are dried during the passage of the container through the drier.

30 A further object of the invention is to provide improved mechanism for traversing the containers through the drier and a special arrangement for applying the air current directly to any container or containers which may be in or passing through the drier regardless of their number or position.

40 A further object of the invention is to provide a drier of this character properly arranged for the most efficient handling of the containers.

In the drawings, which represent one suitable embodiment of the invention, Fig. 1 is a side elevation, partly broken out to expose interior parts; Fig. 2 is a plan view; Fig. 3 is an end elevation on a larger scale from the left in Fig. 1, the driving motor being omitted; Fig. 4 is a broken out longitudinal section of one of the containers; 45 Fig. 5 is a cross section thereof on the line 5-5, Fig. 4; Fig. 6 is a detail longitudinal section showing a modification; Fig. 7 is a cross section on the line 7-7, Fig. 6; and Fig. 8 is a detail view showing a modified 50 form of container and feeding shaft.

The drying apparatus shown in the drawings comprises a relatively long hollow frame or casing 1 of any suitable form, its length depending upon the speed with which the containers are to be moved therethrough and the time required for drying the material to be treated. Said casing may, for example, be twenty to thirty feet long. In one of its side walls it is provided at intervals with a series of hinged windows 2 enabling the interior to be inspected and also providing access to the inner chamber 2^a for cleaning or repairs. In the bottom of the casing and extending from end to end thereof are a series of pipe coils 3 communicating with a supply of steam or other heating medium for heating the air which is to be circulated through the containers for the material to be dried. Preferably said steam coils or pipes are in a long chamber 4 formed by imperforate walls 4^a spaced above the floor so as to form a heating channel extending from end of the casing and open at one end thereof to the atmosphere, as at 5. Above the upper wall 4^a are metal sheets 6 forming another longitudinally extending channel 6^a communicating through an opening 6^b with the far end of channel 4. The upper wall of channel 6^a is perforated to allow the heated air to flow into chamber 2^a.

55 Figs. 6 and 7 show a modified form in which the central portion of the upper wall 4^a is omitted, the bottom wall 4^a being provided at each section of the machine, that is to say one for each fan or blower, with a main slide 4^b on which are adjustable shutter slides 4^c. In this form the chambers 4 and 6^a of the form first described are merged into one chamber closed at both ends and open to the air through the shutters 4^c in 60 slides 4^b. By opening one or more of the shutters 4^c the flow of air upwardly at each section of the machine can be adjusted to as fine a degree as desired and efficiency thereby increased. The main slides 4^b can be opened for clean out purposes.

65 Above the steam coils are suitable supports 7 carrying rollers 7^a to support a pair of longitudinally extending shafts 8, shown as hollow pipes. These shafts are parallel to each other and extend outwardly from both ends of the casing and are inclined slightly from the feeding end, at the right in Fig. 1, to the discharge end of the casing. Suitable means is provided for rotat-

ing said shafts at uniform speed in the same direction. For this purpose the two shafts are provided with sprockets 9 of the same diameter and connected by a chain 10, and 5 one of said shafts is connected by gears 11 to suitable driving means, such as the electric motor 12, which is preferably a variable speed reversible motor, so that the shafts can be rotated in either direction and 10 at any suitable speed.

Some distance above the shafts 8 the chamber 2^a within the casing is provided with a ceiling consisting of a series of vanes or dampers 13 each of which is provided 15 with a normally depending arm 14, said arms preferably lying at the center or midway between the sides of the casing. This ceiling forms the bottom wall of a series of suction chambers 15 each of which chambers 20 communicates by a pipe 16 with a suitable suction fan or blower 17 having an outlet 18. If desired, the several outlets may be connected to a common conduit 19, which may lead to any suitable discharge point 25 or if desired may return all or a portion of the air to the bottom channel 4 for re-circulation in accordance with well known principles. In this latter case the pipe 19 will be provided with a proper damper or dampers 19^a for controlling the air flow.

The returning air current may be passed through a suitable drier or dehydrator, indicated conventionally at X. This drier 35 will contain some drying material, such as concentrated sulphuric acid or calcium chloride in suitable vessels, said material absorbing the moisture in the air so that it is returned to the heating chamber in drying condition with maximum drying qualities.

40 The several fans 17 may be driven in any suitable manner and are shown as driven by belts 20 passing over pulleys 21 on a shaft 22 which is driven at one end by a belt 22^a from the pulley of a motor 23, which may also be 45 a variable speed motor.

At one side of the casing, and preferably on the side opposite to the windows 2, is a suitable frame work 24 supporting a pair of angle irons 25 forming a track or run-way 50 inclining downwardly from the discharge end at the left in Fig. 1, to the feeding end of the machine. At the discharge end is located a suitable table 26 which is at the end of the run-way 25 and at one side of the shafts 8 and at about the same level. At the 55 feeding end of the machine is located another table 27 which is at about the same level as both the run-way 25 and the shafts 8. This table is at the ends of the shafts 8 and is transversely opposite a series of rollers 28 carried in a frame work at the end of the run-way 25 so that a container can be 60 readily rolled off from the run-way upon the table 27. The top of the table 27 may be 65 rotatable about a vertical axis if desired.

With the drier so far described are used a series of containers for the material to be dried, one of said containers being shown in Figs. 4 and 5. The container is of hollow drum form, being provided with cup-shaped end caps or heads 30 one of which is provided with a hinged door 31 having a suitable latch 32, said end heads being connected by longitudinally extending ribs and re-enforcing members 33, shown as formed 70 of angle irons, while the cylindrical wall of the container is formed of wire mesh screen 34.

The container to be filled is placed upon the loading table 27 at the feeding end of the machine with its door open as shown in Fig. 1. After loading it with material the door is closed and latched and the container is turned around until its axis is parallel with the length of the machine, in which position it is placed upon the rotating shafts 8. The rotation of these shafts produces rolling rotation of the container about its own axis. The inclination of said shafts also produces a progressive travel of the container along the shafts at a relatively low rate of speed. The container is either permitted to travel by its own motion or it is pushed through a suitable door 40 at the entrance to chamber 2^a after which it travels slowly along the shafts until it passes the outlet door 41 and reaches the discharge position at the left in Fig. 1. As the container travels along it engages in turn the several depending arms 14 connected to the dampers 13 so that at all times the drum holds open a series of dampers directly above it. As a result, whether one or several of these containers are in the machine, only 95 those dampers are opened which are directly above said containers. The air caused to flow by the several suction fans is therefore compelled to travel in a long tortuous path through the channel 4 at the bottom of the machine over and around the heating pipes and then through chamber 6^a and out 100 through the perforated plate 6 and through the containers. The material in the containers is tumbled or turned over and the heated air passing therethrough absorbs the moisture and carries it away. When the container passes the outlet door 41 it is rolled off laterally upon the table 26 and is unloaded, after which it is placed upon the return track 25 and rolls back by gravity to be 105 filled and again sent through the drier.

Fig. 8 shows another modification in which the shafts 8 are provided with suitable threads 8^a which engage a suitable part of the rolling container and produce positive 115 forward feed thereof. In the form shown the peripheral wall of one of the end heads 30 of the container is provided with a groove or channel 30^a for this purpose. When such an arrangement is used the shafts 8 of course 120

must rotate in the same direction and not reverse, if the container is to be fed in one direction only.

With this apparatus different batches of material may be loaded into different containers and sent through without special marking, except as it may be necessary to mark the several containers. The speed of drying depends upon the rate of travel of the containers through the machine, which can be readily regulated by varying the speed of the motor 12. Variation in the speed of motor 23 will also vary the rate of air flow and to that extent will also affect the drying conditions.

What I claim is:

1. Drying apparatus comprising a drying chamber, means for moving materials to be dried into and out of said chamber, and means for supplying and automatically controlling the flow of drying fluid to and from said chamber.

2. Drying apparatus comprising a drying chamber, means for moving materials through said chamber, and means controlled by the passage of the materials through said chamber for subjecting said materials to drying action.

3. Drying apparatus comprising a drying chamber, means for moving materials through said chamber, and means for forcing a drying fluid through approximately only the area occupied by the materials at a given point of travel through said chamber.

4. Drying apparatus comprising a drying chamber, a heating chamber, a fan chamber, means for moving materials through said drying chamber, and means controlled by the travel of the materials through said drying chamber for placing said several chambers in communication.

5. Drying apparatus comprising a drying chamber, means for moving containers into and out of said chamber, and means for automatically supplying a drying medium to said chamber according to the number of containers in said chamber.

6. Drying apparatus comprising a drying chamber, a heating chamber, a series of fan chambers, means for moving materials through said drying chamber, and means for automatically and successively effecting communication between said several fan

chambers and said other chambers during the travel of the materials through said drying chamber.

7. Drying apparatus comprising a drying chamber, a heating chamber in communication therewith, a fan chamber, means for moving a container into and out of said drying chamber, and valve means controlled by movement of the container in said drying chamber for controlling communication between said fan chamber and said other chambers.

8. Drying apparatus comprising a heating chamber, a drying chamber in communication therewith and located thereabove, means located above said drying chamber for forcing a drying medium from said heating chamber through said drying chamber, means within the drying chamber adapted to be actuated for moving a container through said drying chamber, and means located to one side of said drying chamber for returning the container to the entrance end of said drying chamber.

9. Drying apparatus comprising a heating chamber, a drying chamber in communication therewith and located thereabove, means located above said drying chamber for forcing a drying medium from said heating chamber through said drying chamber, means for moving a container through said drying chamber, means located to one side of said drying chamber for returning the container to the entrance end of said drying chamber, and a return air connection from said last named means to the heating chamber, said parts being so constructed and arranged that the container returning means is substantially surrounded by the circuit of air.

10. Drying apparatus, comprising a drying chamber, a heating chamber, means for circulating heated air from the heating chamber through the drying chamber, a dehydrator, means for conducting the air issuing from the drying chamber through the dehydrator to the heating chamber, and an adjustable connection to the atmosphere arranged in said last named conducting means.

In testimony whereof I hereby affix my signature.

EMIL J. CARROLL.
